US00D888097S

(12) **United States Design Patent** (10) Patent No.: **US D888,097 S**
Butcher et al. (45) Date of Patent: **** Jun. 23, 2020**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Gary Butcher**, San Jose, CA (US);
Alan C. Dye, San Francisco, CA (US);
Chance Graham, Campbell, CA (US);
Jonathan P. Ive, San Francisco, CA
(US); **Christopher Wilson**, San
Francisco, CA (US)

(73) Assignee: **Apple Inc.**, Cupertino, CA (US)

(**) Term: **15 Years**

(21) Appl. No.: **29/694,355**

(22) Filed: **Jun. 10, 2019**

Related U.S. Application Data

(63) Continuation of application No. 29/665,852, filed on Oct. 8, 2018, which is a continuation of application

CLAIM

The ornamental design for a display screen or portion thereof with graphical user interface, as shown and described.

DESCRIPTION

The FIGURE is a front view of a display screen or portion thereof with graphical user interface showing the claimed design.

The outermost broken lines in the FIGURE show a display screen or portion thereof and form no part of the claimed design. The other broken lines in the FIGURE show portions of the graphical user interface that form no part of the claimed design.

1 Claim, 1 Drawing Sheet

Related U.S. Application Data

No. 29/629,969, filed on Dec. 18, 2017, now Pat. No. Des. 830,410, which is a continuation of application No. 29/604,780, filed on May 19, 2017, now Pat. No. Des. 805,550, which is a continuation of application No. 29/572,138, filed on Jul. 25, 2016, now Pat. No. Des. 787,533, which is a continuation of application No. 29/501,164, filed on Sep. 2, 2014, now Pat. No. Des. 762,659.
